UNITED STATES PATENT OFFICE

FRANK Z. AHL, OF SACRAMENTO, CALIFORNIA

FURNACE CONSTRUCTION

Application filed June 6, 1927. Serial No. 196,675.

This invention relates to a hot air furnace, and particularly pertains to a furnace adapted to be used in heating dwellings and the like.

It is common practice to construct hot air furnaces with linings which resist the action of combustion within the fire-box of the furnace, and which maintain their shape irrespective of the temperature created by combustion. In most instances these linings are of such design and construction as to make them difficult to prepare and to maintain in the condition which will prevent them from overheating. It is the principal object of the present invention, therefore, to provide a furnace structure in which a peculiar type of segmental interlocking lining of metal is provided, which lining is substantially self-supporting in its assembled position, thus creating an air space between the side wall of the fire-box and the lining whereby additional air to support the combustion of otherwise unburned gases may be provided, and whereby the lining will be maintained at such a temperature as to prevent it from being burned away.

The present invention contemplates the use of a furnace having the usual air jacket within which is disposed a fire-box, which fire-box is lined by a plurality of interlocking lining members.

The invention is illustrated by way of example in the accompanying drawings, in which:

Fig. 1 is a view in central, vertical section through the furnace, showing the structure with which the present invention is concerned.

Fig. 2 is an enlarged view in perspective, showing the lining of the furnace with parts broken away for the sake of clearness.

Fig. 3 is an enlarged view in perspective showing a lining member as used along one side of the feed door.

Fig. 4 is a view in perspective showing one

of the lining members used in the body of the fire box.

Fig. 5 is an enlarged view in perspective showing one of the lining members forming the bottom of the feed door.

Fig. 6 is a view in perspective showing a form of grate which I employ in connection with my invention.

Fig. 7 is a view in perspective showing the details of one of the lining members.

Referring more particularly to the drawings, 10 indicates the cylindrical air jacket of the furnace. This jacket is fitted at its upper end with a dome 11 to which is connected a plurality of hot air conduits 12. The lower end of the cylindrical jacket 10 is closed by a bottom member 13. Disposed within the cylindrical air jacket structure is a fire-box 14. This fire-box is here shown as also being cylindrical in shape and as being of such a diameter as to create an air circulating space between the outer shell 10 and the shell of the firebox. The lower end of the fire-box is formed with an outlet opening 15, normally covered by a door 16. The floor of the firebox structure 14 is indicated at 17, and is spaced from the main floor 13 to provide an air circulating space which will act to cool the floor 17. Disposed upon the upper end of the fire-box structure 14 is a dome 18 closing the same and preventing the products of combustion from passing into the air chamber and from thence to the registers of the furnace through the pipes 12.

Formed in one side of the fire-box 14 is an opening 19 communicating with a firing door passageway 20. This passageway extends through an opening in the outer side wall 10 of the furnace, the passageway and opening being normally closed by a firing door 21. At the opposite side of the fire-box wall is an outlet opening 22 in communication with a flue chamber 23 and a flue pipe 24. It is understood that products of combustion

from the fire-box may pass outwardly through the opening 22 to the flue 24.

It may be found desirable to burn wood, coal or oil in the furnace, in which event various rearrangements of the grate structure 52 may be necessary. When wood or coal is to be burned, the grate 54 may be placed upon a grate ring 25. Any type of grate may be used in place of the one indicated in Fig. 6 of the drawings. In any event it is essential that the fire-box shall be lined to prevent oxidation of the metal side walls of the fire-box. This is done in the present instance by providing the lining 26, which comprises a plurality of interlocking segments supported upon the grate ring 25. The grate ring is carried upon flanged members 27, secured to the inner faces of the fire-box side wall. This grate ring is formed with an annular center portion 28 terminating at its lower end in an inturned supporting flange 29, and at a point near its upper end in a horizontally projecting annular flange 30. Circumscribing annular ribs 31 are carried upon the flange and spaced a distance therefrom to provide an annular groove 32, into which the lips along the lower edges of the segmental lining members may project. The lining members are preferably formed of metal. The lining is essentially constructed of a plurality of segments 33, as indicated particularly in Fig. 4 of the drawings, and the necessary door framing segments 34 and 35, as indicated in Figs. 3 and 5 of the drawings. The segments 33 comprise body portions 36, which are arcuate in horizontal cross section and are of any desired vertical length. These body portions are formed along one edge and the lower end with flanges 37 and 38 respectively which overhang the side and edge of the body portion 36. The opposite edge of the segment 33 from its edge 37, is formed with a flange 39 which is oppositely offset from the flange 37, and is complementary to the flange 37 of a contiguous lining segment 33 when the segments are assembled. The upper end of the flanges 39 on the lining segments 33 follow the contour of the end of the segments, and are recurved to terminate in a locking lug 40, which is substantially parallel to the flange 39 and is spaced a distance therefrom to form a mortise 41 substantially equal to the thickness of the flange 37, and of such formation as to conform to the contour of the upper end of the flange 37 of the contiguous lining segment 33 when the segments are assembled. It will be understood that when the lining is assembled the projecting flanges 38 of the lining sections will extend into the annular channel 32 occurring between the ribs 31 of the grate ring. In order to fit the firing opening and to prevent the products of combustion from seeping through the joints of the firing opening and into the air circu-

lating chamber, it is desirable to make a neat and tight joint between the lining members and the firing opening. This is done in the present instance by use of lining segments 34 and 35. The segments 34 are formed with flanges 42, which extend horizontally and meet the edges of the firing opening casting 20. The segment 34 is also provided with locking lugs upon each side, as is clearly shown in Fig. 3. As a result of this construction, it will be seen that it can be moved vertically out of engagement with the remaining segments and when so removed, the remaining segments can then be separated and removed one by one by a slight sidewise movement. The segments 35 are formed with enlarged out-turned flanges 43 at their upper ends, which flanges abut against the side wall of the fire-box and rest upon small angle members 44 secured to the wall, as shown in Fig. 1 of the drawings. It will be evident that because of the provision of two locking lugs upon the segment 34, no locking lug will be required upon the adjacent segment for the purpose of holding these two segments in locked engagement. Such a modified segment is shown in Fig. 7 of the drawing and is designated by the numeral 46. By this arrangement it will be seen that when any section of the fire-box lining has become damaged it may be readily lifted out of its place and a new section substituted where needed by first removing the section 34, which may be termed a key section, and then removing the sections between it and the damaged section. It will further be evident that by the use of an interlocking and practically self-supporting lining it is possible to create an air passageway 45 between the side wall of the fire-box 14 and the lining 26, thus permitting a circulation of air to be created through the lower door of the furnace and upwardly along the passageway 45 and into the combustion space in the top of the fire-box. It has been found that certain of the gases do not burn, due to the fact that they do not have sufficient oxygen to support combustion, and that when air is supplied to the top of the fire-box in the manner here described, additional burning of combustible material will take place, thus making a hotter fire and at the same time keeping the fire-box in a relatively cool condition. It will also be evident that by creating a circulation of air between the lining and the metal side wall of the fire-box the side wall will be protected by air insulation, which will prevent the high temperature of the lining from being transmitted to the wall of the fire-box.

While I have shown the preferred form of my invention, it is to be understood that various changes may be made in its construction by those skilled in the art without

departing from the spirit of the invention, as defined in the appended claim.

Having thus described my invention, what I claim and desire to secure by Letters Patent is:—

5 A fire-box of the character described comprising a plurality of vertically extending cooperating sections, flanges formed on the vertical edges of said sections, and locking lugs carried by the upper edges of said sections for maintaining the flanges of adjacent sections in cooperative relation with each other.
